UNITED STATES PATENT OFFICE

GEORGE DRAKE, OF LINDEN, NEW JERSEY

ENGINE PISTON

Application filed April 8, 1930. Serial No. 442,485.

This invention relates to pistons for engines, such as internal combustion motors and similar motors working under pressure, the object of the invention being to produce 5 a novel form of piston in the operation of which piston rings may be dispensed with.

It is also an object of the invention to provide a piston for engines by which the friction between the piston and the inner wall 10 of the engine piston is reduced to a minimum, in which also the possibilities for piston slap and for the scoring of the cylinder walls are divided.

It is a further object of the invention to 15 provide a piston which will increase the contact between the cylinder wall and the piston so as to bring about a high compression and expansion without any losses whatever and without any distortion of the cross 20 section of the piston.

With these and other objects in view which will be hereinafter apparent, the invention consists in the combination and arrangement of various parts as described below and 25 illustrated in the accompanying drawings in which

Figure 1 is a front elevation of one form of my new piston;

Figure 2 is a side elevation of the same;

Figure 3 is a vertical sectional view on line 3—3 of Figure 5;

Figure 4 is a vertical sectional view on line 4—4 of Figure 5.

Figure 5 is a top view of the piston illustrated in Figures 1—4, with the detachably arranged head thereon;

Figure 6 is a top view of the same piston with the head removed therefrom;

Figure 7 is a perspective view of the head 40 of the piston; and

Figure 8 is a vertical sectional view, similar to Figure 4, of a piston having the wall arranged in a different way, but being otherwise unchanged.

Like numerals denote like parts in all figures.

Referring to the drawings the numeral 10 denotes a pressure receiving head consisting of a compression ring 11, having a slot 12 cut 50 in any suitable direction. The upper part

of the compression ring 11 is reduced in its inner dimensions in upwardly decreasing proportions, whereby the shoulder 13 and the rim 14 are formed; both shoulder 13 and this rim 14 forming the walls of the groove 15 cut into the inner wall of the cylindrical part 11. An open framework 16, bent in cylindrical fashion and open at its front, is rigidly secured to, or integrally connected with, the lower rim of the cylindrical part 11 and with the upper rim of a guide ring 17 having the same diameter as the compression ring 11 and provided with a split 18 arranged, as obvious from Figure 1, substantially perpendicularly below the split 12.

It will be noticed from Figure 2 that the diameter of the cylinder formed by the open framework 16 is slightly smaller than that of the compression and guide rings 11 and 17, respectively, and that therefore, if inserted tightly into the cylinder (not shown) of an explosive engine, the parts of the frame-work 16 will not come into contact with the walls of aforesaid cylinder.

In substantially the middle of the piston 75 wrist pin bearings 19 and 20 are arranged oppositely to each other and equidistantly from the horizontal axis of the piston, both bearings 19 and 20 being integrally connected with the framework 16.

From Figure 1 and particularly from Figure 2 it is apparent that the framework 16 is bent into cylindrical shape; there is, however, another relation established by the parts of this framework 16 insofar as the bearings 19 and 20 are concerned, because as seen from the outside rim of these bearings 19 and 20, the parts of the framework, extending substantially radially from the rims of the bearing to the lower and upper rings 11 and 17, respectively, so as to form with the outer rims of these journals a truncated cone and thus with a minimum of material evenly support the respective parts, to which they are joined.

Figure 7 illustrates a dome-shaped annular plate 21 having a curved, dome-shaped upper surface 22 and a prismatic body 23, having a concentric, arc-shaped peripheral extension 24, which projects beyond the outer 100

rim of the cylindrical body 11. An elastic double bent flat spring 25 is secured at one end to the plate 21, at its under side in the middle of the same, while the free end depends and in its normal position presses against the inside wall of the framework 16, the point of contact being opposite to the split 12.

From Figure 3 it is obvious that the dome-shaped plate 21 rests safely upon the shoulder 13 all around the inner cylindrical wall of the part 11 and even reaches into the groove 15, leaving in its normal position a small free space all around its edge and between the outer wall of the said groove 15 and in this position the plate 21 is normally held by an arc-shaped spring 29 interposed, in part in the groove 15, between said plate 21 and the peripheral extension 14, the spring 25 reaching almost all around the plate 21 terminating shortly on both sides of the prism 23 projecting from the plate 21.

Furthermore the bearings 19 and 20 are rigidly connected with the main column 26 of the framework 16, by two horizontally disposed, arc-shaped ribs 27 and 28, respectively.

Figure 8 illustrates a piston which in every respect is the same as the one illustrated in Figures 1-7. Its difference from the other piston is best described by saying that the piston described above is cut in two parts by a horizontal section through its middle, that the lower section is turned around 180° and then joined again to the upper half. This reversion of the lower half of the piston brings in the new form thus obtained thereby the split 18, of the lower cylindrical part 17, diagonally opposite to the split 18.

Furthermore, instead of having only one main column 26, as seen in Figures 1, 2, 3 and 4, we have now two main columns 26^a and 26^b, slightly longer than one half of column 26, on the right and left side, respectively of the new piston illustrated by Figure 8.

It is self-evident, that this new piston is open on the side where the splits 12 and 18 are located, i. e. at the upper left side below split 12 and above column 26^b, and at the right side above split 18 below the main column 26^a. Columns 26^a and 26^b are connected, with the apertures, serving as journals for the wristpins, by the ribs 31 and 32.

The prismatic body 23 could of course not cover and could not protrude beyond the outer rim of the cylindrical part 11 unless on both sides of the split a recess 30 was provided in the rim of the compression ring 11. It is of course necessary that the depth of this recess is not deeper than the thickness of the prismatic body 23, which substantially is that of the greatest thickness of the plate 21, that is at its center.

Furthermore this recess 30 must not be wider than necessary to let the prismatic

body 23 pass freely in the same and its position must be such that said prismatic body 23 covers the split 12.

In regard to the service and the operation of the piston I wish to say the following:

It is apparent from the sections of the compression ring 11, Figures 3 and 4, that the plate 21 rests fully all around upon the shoulder 13 and covers the split 12 so that the piston is fully covered at its upper part and assuming that, thermal expansion taken into consideration, it is in proper contact with the inside wall of the cylinder, proper compression of the gas mixture and expansion of the same after explosion is fully guaranteed. To insert the piston, as described above, into the cylinder of an engine, one has first to push the prismatic body 23 so far inwardly that it will not obstruct any more the insertion of the piston. This having been accomplished the spring 25 constantly pushes the body 23 against the cylinder wall and thus guarantees that the opening of the split 12 is always fully covered so as to prevent the compressed or expanding gases from escaping without having given off the energy expected from them. Moreover, the arc-shaped spring 29 continuously keeps down the plate 21 upon the shoulder 13 and its inwardly disposed terminals, pressing upon the plate 21, to assist the action of the spring 25 pressing the plate 21 towards the wall of the cylinder of the engine.

What I claim is:

1. In a piston of the class described, the combination comprising a pressure receiving head consisting of a split compression ring, and a horizontal plate slidably arranged in air-tight engagement with the said split compression ring.

2. In a piston of the class described, the combination of a pressure receiving head consisting of a split compression ring having in its upper inside wall an annular groove, a recess cut in the wall of said ring at the split and extending on both sides of the split and to the base of said annular groove, and a horizontal plate slidably arranged within the said annular groove and in air-tight engagement with the said split compression ring, said plate having an extension operatively arranged in the said recess to seal the split in said compression ring.

3. In a piston of the class described, the combination of a pressure receiving head consisting of a split compression ring having an annular groove in its upper inner wall, a recess cut in the wall of said ring at the split and extending on both sides of the split and to the base of said annular groove, and a horizontal plate slidably arranged within the said annular groove and in air-tight engagement with the said split compression ring, said plate having an arc-

shaped peripheral extension protruding through said recess to the outer wall of said compression ring to seal the split in said compression ring.

5 4. In a piston of the class described, the combination comprising a pressure receiving head consisting of a split compression ring having an annular groove in its upper inner wall, a recess cut in the wall of said compression ring at the split and extending on both sides of the split and to the base of said annular groove, a dome-shaped plate, having an arc-shaped peripheral extension protruding through said recess, slidably arranged in 10 said annular groove, the said extension extending to the outer wall of said compression ring, and an arcuate elastic ring superimposed upon the said plate in the said annular groove adapted to maintain the said 15 plate in air-tight engagement with the said split compression ring.

20 5. In a piston of the class described, the combination of a pressure receiving head consisting of a split compression ring having an annular groove cut in its upper inner wall, a recess cut in the wall of said ring at the split, a dome-shaped plate slidably arranged in said annular groove having an arc-shaped peripheral extension protruding through the 25 said recess to the outer periphery of said split compression ring, an arcuate elastic ring superimposed upon said plate in the said annular groove adapted to maintain the said plate in air-tight engagement with the said 30 split compression ring, and a double bent flat spring secured at one end to the lower side of said dome-shaped plate and having its other end in engagement with a part of the piston to urge the said arc-shaped extension into sealing engagement with a cylinder 35 wall.

40 6. In a piston of the class described, the combination comprising a pressure receiving head consisting of a split compression ring, having an annular wall portion, and a substantially annular horizontal plate slidably arranged within and near the upper rim of the said annular wall portion, means for retaining said annular plate in air-tight engagement with said wall portion, an open framework integrally formed with the wall portion of said split compression ring at its upper end and having a split guide ring integrally formed at its lower end, said open 45 framework being of less diameter than said compression or guide rings, and coaxially arranged wrist pin bearings formed in the said open framework and connected by integral struts to both the said split compression ring and the said split guide ring.

55 7. In a piston of the class described, the combination comprising a pressure receiving head consisting of a split compression ring having an annular groove formed in its upper inner wall and a recess cut in the wall at

the split and extending to the base of the said annular groove, a dome-shaped plate slidably arranged in the said annular groove having an arc-shaped peripheral extension protruding through the said recess to the outer periphery of said split compression ring, an arcuate elastic ring superimposed upon the said dome-shaped plate in the said annular groove adapted to maintain the said plate in air-tight engagement with the said split compression ring, a double bent flat spring secured at one end to the lower side of said dome-shaped plate and having its free end in engagement with a part of the piston opposite the split to urge the said arc-shaped extension into sealing engagement with a cylinder wall, an open framework comprising the body of the piston integrally formed with the said split compression ring and having a split guide ring at its lower extremity, and co-axially arranged wrist pin bearings formed in said open framework and connected by integral struts to both the said split compression and split guide rings.

8. In a piston of the class described, the combination comprising a pressure receiving head consisting of a split compression ring having an annular groove formed in its upper inner wall, a recess cut in the wall of said split compression ring, at the split, and extending to the base of said groove, a dome-shaped plate slidably arranged in said annular groove having an arc-shaped peripheral extension protruding through said recess to the outer periphery of said wall, an arcuate elastic ring superimposed upon the said dome-shaped plate in the said annular groove adapted to maintain the said plate in air-tight engagement with the said split compression ring, a double bent flat spring secured at one end to the lower side of said dome-shaped plate and having its free end in engagement with a part of the piston opposite the split to urge the said arc-shaped extension into sealing engagement with a cylinder wall, and an open framework having co-axially arranged wrist pin bearings and a split guide ring, the said open framework connecting each of the said wrist pin bearings at its outer edges in cone-shaped fashion with the rim of both the said compression and guide rings with the splits in said rings vertically aligned with respect to each other.

100 In witness whereof I have hereunto set my hand.

110 GEORGE DRAKE.
